METALLIC BED

Solomon Raduns, Brooklyn, N. Y., assignor to
Greenpoint Metallic Bed Company, Inc., Brook-
lyn, N. Y.

Application January 24, 1938, Serial No. 186,505

1 Claim. (Cl. 5—280)

The present invention relates to a metallic bed construction and it particularly relates to a novel method of combining the panel with the tubular frame of the foot and head pieces of metallic beds.

In my copending application, Ser. No. 114,599, filed December 7, 1936, which has matured into Patent No. 2,106,657, January 25, 1938, there is disclosed a metallic bed construction in which a panel is held upon a tubular U-shaped frame by a welded connection to said tubular frame.

The connection is preferably formed by providing a folded member or a U-shaped member, the recess of which faced inwardly and the sides of which were pressed together to grip and firmly hold the periphery of the panel or plate covering the U.

In one construction the inside flange or leg of the U was spot-welded or seam-welded to the tubular frame, while in another embodiment the panel itself was connected by welding or spotting to the frame and the periphery of such panel was flanged and turned over and inwardly to cover the welding.

Among the objects of the present invention are to provide other improved panel constructions for the head piece and foot piece of metallic beds, in which the panel will be closely united with the frame, although separate therefrom, without the necessity of slotting or otherwise affecting the structural integrity of the frame.

Another object is to provide artistic head and foot piece constructions for metallic beds, in which, although the panel will be unitarily joined to the frames of tubular stock, such junction will not weaken either the panel or frame construction, and may be readily and inexpensively made without detracting from the artistic appearance of the bed and decorative effect thereof.

A further object is to provide improved close attachments of bed panels to the foot and head frames of such beds, which not only will not detract from the artistic appearance of the bed construction, but in addition will eliminate movement or looseness between the panel and bed frame, and give the bed better sound deadening properties.

Other objects will be obvious or will appear during the course of the following specification.

In accomplishing the above objects it has been found most satisfactory to form the frame of tubular stock which may consist of welded tubing or rolled-intubing, shown of square cross-section but also possibly of other polygonal or circular cross-sections.

The U-shaped strips or the other holding strips may be attached to the outside or rear faces or even the inside faces of the U-shaped tubular frames and desirably the recesses of such U-shaped holding strips may face outwardly so that the flanges on the peripheries of the panels will be turned inwardly. The peripheries of the panels may also be turned over the tubular frame members to engage or overlie one or more sides thereof and in certain instances portions of the tubular frame may be extended to form the holder strips.

In other forms, flanges on the ends of the panels may be caused to extend into tubular end frames adjacent to the corners thereof, but this last mentioned construction is generally not preferred.

In the accompanying drawing are shown several of the various possible embodiments according to the present invention, to which the present invention is, however, by no means restricted since many changes and alterations may be made therein, all within the scope of the invention, this drawing being by way of illustration only and not by way of limitation.

In the drawing,

Fig. 1 is a perspective view of a metallic bed and construction, the foot piece being illustratively shown.

Fig. 2 is a transverse fragmentary section view upon the line 2—2 of Fig. 1 and upon an enlarged sectional view as compared with Fig. 1.

Figs. 3 to 12 are respectively fragmentary transverse section views of alternative bed end construction similar to Fig. 2.

Referring to Fig. 1, the bed is provided with a tubular frame structure A, which may consist of folded or welded tubing, which is shown in the present illustration as of square cross-section. It is obvious, however, that this tubing may be of other cross-sections, such as hexagonal, triangular, octagonal, round, oval, and it may carry various forms of ornamental grooving or ridging. The tubing is preferably unsplitt and is of such a form as will not tend to separate upon stress or strain being applied thereto.

As shown in Fig. 1, the tubing A is of an inverted U-shape but other forms may be employed and the tubing may be employed solely at the sides of the bed. There may also be additional tubing extending across the bed structure and between the legs of the inverted U at various levels.

The panel B, which is of sheet metal, is preferably connected with the U-shaped frame A by a welded connection and desirably the peripheral

portions of the panel B are not directly connected, as by welding, to the frame A but are indirectly connected by means of a holder strip, which holder strip may be of U cross-section with one of its legs permanently connected with the frame or connected to the frame by welding. The welding may be seam-welding, spot-welding or equivalent other types of welding.

In some constructions the periphery of the panel may be directly connected at its periphery to the frame by welding, and a flange member or structure is also preferably provided extending inwardly over or under the periphery of the panel.

Referring particularly to Fig. 2, the frame A is composed of the tubing 10 of square cross-section, said tubing having a front wall 11, a rear wall 12, an outside wall 13, and an inside wall 14.

Attached to the tubular member 10 at the wall 11 is the U-shaped holder C, which has an inside leg 15 which may be spot or seam welded to the face 11 of the tubular member 10 at 16. The U-shaped member C is also provided with an outside leg 17.

The periphery 25 of the frame B is provided with an inturned flange 18 which fits between the flanges 15 and 17 and abuts the bottom of the recess between said flanges 15 and 17. The outturned flange 17 at its end abuts the bottom of the recess between the periphery 25 of the panel B and the inturned flange 18.

Preferably the flange 18 is clamped between the flanges 15 and 17 while the flange 17 is clamped between the flange 18 and the periphery 25 of the panel B.

In applying the panel B to the frame A, the U-member C may first be applied by the connection 16. Then if desired, the legs 20 may be pressed together in the directions indicated by the arrows 21 and the panel B may be slid into position from the top of the bed in the direction 22 with the inturned flange 18 engaging and being received in the recess of the U-member C.

Then the legs 20 are permitted to spring apart in the directions indicated by the dotted arrows 23, which will result in the panel being subjected to a substantial lateral tension by the legs tending to move outwardly in the direction 23.

This construction gives a very satisfactory bed end which will have a minimum of resonance and which will stand up under varying conditions. To cause closer contact between the flanges 15, 17 and 18 a pressure roller may be run around the periphery 25 of the construction of Fig. 1 after the assembly above described.

In Figs. 3 to 12 are shown alternative embodiments in which corresponding parts are indicated by the numerals in Figs. 1 and 2, respectively provided with a superior prime, 2, 3, 4, 5, 6, 7, 8, 9 and 10.

In all these figures the forward end of the bed of the half of the bed as shown in Fig. 1 faces in the direction 24.

In Fig. 3 the welded connection 16' is directly attached to the periphery 25' of the panel B' and the inturned flange 18' overlies the front of the panel B'.

In Fig. 4 the panel B² has portions 26, 27 and 28 respectively encircling the sides 11², 13² and 12² of the member A². The flange 25² extends over the inside face 14² of the bed and has a welded connection 16².

The holder member C² has one portion 29 overlying the portion 13² of the frame A² and 27 of the panel B², and it is provided with the

end legs 30, having the inturned flanges 31, which are provided with a welded connection at 32 to the members 26 and 28 respectively. In this construction the legs 20² may be permitted to spring back into the recess between the elements 26, 27 and 28, as shown by the arrows 23 in Fig. 1.

Then the flange 25² may be inturned and welded and finally U-member C² may be attached.

In Fig. 5 the periphery 25³ has an inturned flange 18³ which is welded at 16³ to the wall 11³ of the frame.

In Fig. 6 the periphery 25⁴ of the panel B⁴ has an inturned flange 18⁴ welded at 16⁴ to the wall 11⁴ of the member 10⁴. The angle member 35 has the flanges 36 and 37 respectively spot-welded at 38 and 39 to the panel B⁴ and the wall 14⁴.

In Fig. 7 the wall 11⁵ is provided with an extension 40 which is turned inwardly over the wall 11⁵ and over the periphery 25⁵ of the panel 35. The welding 16⁵ serves to connect the flange 40 to the panel B⁵.

In Fig. 8 both the wall 13⁶ and the wall 11⁶ are provided with an extension 41, the inner side of which is spot-welded at 16⁶ to the periphery 25⁶ of the panel B⁶.

It will be noted that in Figs. 7 and 8 the attachment flanges extend from the corners 42 and 43 of the members A⁵ and A⁶ without splitting said members or weakening them.

In Fig. 9 the flange 18⁷ may be folded inside of the corner 44 of the element A⁷ and it may lie against the inside face of the wall 11⁷ and be connected thereto by the welding 16⁷.

In Fig. 10 the flange 18⁸ is inturned to lie against the wall 13⁸ to which it is connected by welding 16⁸.

In Fig. 11 the U-member C⁹ is positioned on the back wall 12⁹ of the member A⁹ and the panel B⁹ has portions 45 and 46 extending around the tubular structure 10⁹. The inner leg of the U-member C⁹ may be welded to the wall 12⁹ of the member 19⁹.

In the structure Fig. 12 the U-member 10¹⁰ is placed on the side wall 13¹⁰ of the member A¹⁰ and the flange 46 overlies the wall 13¹⁰.

It is obvious, of course, that the U-members C to C¹⁰ may be positioned at other places than shown either at other corners of the tubular members or spaced inside of the corner. If the tubular members are of different shapes than shown, the side walls of the U-members C may be correspondingly shaped. It is also possible to make the U-members of other forms than shown, and if desired the legs may be of uneven lengths with the inside leg being much longer than the outside leg and being welded to the frame at the extension beyond the outside leg.

The corner extensions 40 and 41 of Figs. 7 and 8 might also be provided in other corners than those specifically shown or at other places in the periphery of the square, octagonal or round tubular members 10.

It is thus apparent that there is provided an improved bed end construction particularly adapted to metallic beds, which will stand up under considerable changes of temperature, which will be readily shipped and stored and which will be able to withstand considerable stress without breakage or separation.

The invention, however, is not intended to be restricted to any particular construction or arrangement of parts, or to any particular application of any such construction, or to any specific

method of operation, or manner of use, or to any of various details thereof, herein shown and described, as the same may be modified in various particulars or be applied in many varied relations without departing from the spirit and scope of the claimed invention, the practical embodiments herein illustrated and described merely showing some of the various features entering into the application of the invention.

What is claimed is:

A metallic bed end construction comprising an inverted U-shaped unsplit tubular frame, said tubular frame having a rectangular cross section and said cross section having front, back, outside and inside walls, a sheet metal panel 15 covering said U and extending between the legs and base thereof, said panel having an inturned

5 peripheral flange, said flange extending over and covering the outside and back walls and extending partly over the inside wall, and a U-shaped holder for the panel, said holder being attached to said flange, said holder consisting of a folded metal strip having a flattened U-cross section, said flange being positioned inside of said folded metal strip and being clamped between the legs of said U-shaped holder, the portion of said flange extending across the outside wall of said frame section being covered by the base of said U-shaped holder and the legs of said U-shaped holder consisting of folded in double thicknesses of sheet metal and being spot welded to the portions of said panel extending across the front and back walls of said frame section.

SOLOMON RADUNS.
